(57) **CLAIM**

The ornamental design for a weighted swing training apparatus, as shown.

DESCRIPTION

The present application is related to U.S. Pat. No. D669,142, filed Aug. 11, 2011, entitled “Weighted Swing Training Apparatus,” to U.S. Design patent application Ser. No. 29/500,634, filed Aug. 27, 2014, entitled “Weighted Swing Training Apparatus,” and to U.S. Design patent application Ser. No. 29/506,288, filed Oct. 15, 2014, entitled “Weighted Swing Training Apparatus.”

FIG. 1 is a perspective view of a weighted swing training apparatus showing my design in accordance with a first embodiment;

FIG. 2 is a front elevational view of the weighted swing training apparatus of the first embodiment;

FIG. 3 is a rear elevational view of the weighted swing training apparatus of the first embodiment;

FIG. 4 is a left side elevational view of the weighted swing training apparatus of the first embodiment;

FIG. 5 is a right side elevational view of the weighted swing training apparatus of the first embodiment;

FIG. 6 is a top plan view of the weighted swing training apparatus of the first embodiment;

FIG. 7 is a bottom plan view of the weighted swing training apparatus of the first embodiment;

FIG. 8 is a perspective view of a weighted swing training apparatus showing my design in accordance with a second embodiment;

FIG. 9 is a front elevational view of the weighted swing training apparatus of the second embodiment;

FIG. 10—is a rear elevational view of the weighted swing training apparatus of the second embodiment;

FIG. 11 is a left side elevational view of the weighted swing training apparatus of the second embodiment;

FIG. 12 is a right side elevational view of the weighted swing training apparatus of the second embodiment;

FIG. 13 is a top plan view of the weighted swing training apparatus of the second embodiment; and,

FIG. 14 is a bottom plan view of the weighted swing training apparatus of the second embodiment.
